UNITED STATES PATENT OFFICE.

GEORGE POLL, OF MELBOURNE, VICTORIA.

SMOOTHING-IRON.

SPECIFICATION forming part of Letters Patent No. 595,075, dated December 7, 1897.

Application filed July 8, 1897. Serial No. 643,894. (No model.)

To all whom it may concern:

Be it known that I, GEORGE POLL, miner, a subject of the Czar of Russia, and a resident of No. 56 Oxford Chambers, Bourke Street, 5 Melbourne, in the British Colony of Victoria, have invented a certain new and useful Improved Smoothing-Iron Heated by Gas Generated from Kerosene or other Oil or Spirit, of which the following is a specification.

10 This invention relates to an improved smoothing-iron which is heated by the combustion of gas generated from kerosene or other oil or spirit, the conversion of the oil being brought about by its being passed through 15 a heated tubular coil arranged within the iron.

I will now describe the invention, aided by a reference to the accompanying sheets of drawings, which illustrate it, in—

20 Figure 1 by a part side view and a part longitudinal section, Fig. 2 showing a back view of the iron and with the oil-reservoir in section; Fig. 3, a front view of the burner, coils, and cup; Fig. 4, an enlarged sectional view of the burner, and Fig. 5 a cross-section of 25 the handle.

The iron proper is in the form of a hollow box A, made of the usual shape in plan and provided with a chimney A' at its fore end, while B is its handle and which is coated with 30 non-conducting material. At the back end of the iron is an oil-supply reservoir C, having attached to its lower end and leading from it into the box a copper tube or pipe C', terminating in a double coil C², said coil being 35 preferably double, with the inner coil within an outer coil and having the end of the outer tube attached at d to a Bunsen burner D; also, the pipe C' has a branch C³, leading from it at c to and entering the upper part of the oil-reservoir C. Around the plain part of the 40 burner is a cup D' in which to hold and burn methylated spirit, by the burning of which the coil is heated in the first instance prior to its being placed in the iron in order to heat 45 the coils to generate the oil-gas. The orifice d' in the throat of burner is very small and in the tube or chamber leading to it is a very fine wire-gauze hood d², the purpose of which is to prevent the choking of the burner.

50 Within the aforesaid oil-reservoir C is a rod E, having at its lower part a valve E', and said rod or spindle passes out through a

screwed gland and stuffing-box E² at top of reservoir in order to receive a key E³, by which the flow of oil may be regulated by the position in which the valve is placed, said valve within the reservoir having a small way e in it passing from its side down its center to the pipe C', leading to the tube or coil. By having a pipe C³, as aforesaid, connecting the 60 gas-generating coil with the top of reservoir the flow of oil is assured by reason of the gas-pressure being upon it. At back of the hollow part of iron a hole is provided, through which to pass the said tubular coil C², the 65 said cup D' fitting neatly in the hole and forming a cover for it.

C⁴ is a pipe provided with a screw cover or cap C⁶, by the removal of which the gas blows out or escapes.

70 The oil-reservoir C is held in position by a suitable pin-and-loop fastening F, which grips the back vertical bar of the handle, and such reservoir and coil are made secure to each other and in such a manner that they are separable from the box-iron, while a suitable capped supply-hole C⁵ is provided in the top 75 of the oil-reservoir.

The handle B is made in two parts—viz., a central bar b² and the asbestos coating b b', the latter being asbestos fiber held in position by a wire-gauze covering and the former, b, a covering of sheet-asbestos. The wire-gauze is indicated by dotted lines b³ between the layers b and b'.

80 To use the iron, the reservoir is first filled with oil, preferably one half kerosene and the other half benzene, and the reservoir and coil being detached from the iron proper the said parts are laid in such a position that the cup 90 D' is horizontal, and in it methylated spirit is placed and ignited in order to heat the coil and so convert the oil in it into gas, and which gas as it issues from the end of the burner D is ignited. Then the coil and reservoir are 95 placed at the positions shown in Fig. 1 in the iron, the issuing gas heating the coil as well as heating the iron, and the pipe C³ leading the gas-pressure to above the oil in reservoir in order to insure a constant supply of oil to 100 the gas-generating tubes or coils.

Having now described my invention, what I claim as new, and desire to secure by Letters Patent, is—

1. In combination the iron box having an open end, a reservoir outside of said box, a burner-tube extending therefrom within the box, and an initial heating-cup on said burner-tube adapted to close the opening in the iron box, substantially as described.
2. In combination with the iron box, the handle therefor comprising the central core, the two layers of asbestos, the inner layer being of loose fibers while the outer layer is of sheet-asbestos, the said inner layer being surrounded by a wire-gauze, substantially as described.
3. The improved smoothing-iron heated by gas generated from kerosene or other oil or spirit consisting essentially of the box A, tubular coil C², burner D, cup D' reservoir C and return-pipe C³ substantially as herein described and shown in the drawings.

In witness whereof I have hereunto set my hand in presence of two witnesses.

GEORGE POLL.
